UNITED STATES PATENT OFFICE.

HARRY F. HITNER, OF WILKINSBURG, PENNSYLVANIA, ASSIGNOR TO PITTSBURGH PLATE GLASS COMPANY, A CORPORATION OF PENNSYLVANIA.

DEVICE FOR SEVERING GLASS.

1,359,172.

Specification of Letters Patent. Patented Nov. 16, 1920.

Application filed November 4, 1919. Serial No. 335,611.

To all whom it may concern:

Be it known that I, HARRY F. HITNER, a citizen of the United States, and a resident of Wilkinsburg, in the county of Allegheny and State of Pennsylvania, have made a new and useful Invention in Devices for Severing Glass, of which the following is a specification.

The invention relates to devices for severing or cracking glass by the application of heat along the desired line of division. The device is primarily designed for cutting up the glass cylinders from which window glass is made, but may be used upon other circular glass articles or even upon flat glass if so desired. The objects of the invention are the provision of a compact and simple device, which can be operated with great rapidity and certainty, which requires little skill in operation, and which is more durable than the type now in use in which the wire is heated by the passage of electricity through the wires.

Briefly stated the device comprises a portable heating chamber carrying a reel upon which a wire or chain is wound. The wire or chain is heated while wound on the reel, and when ready for use is pulled out and placed around the cylinder to be divided. After this operation the wire is wound back into the reel, preferably by means of a spring, although this may be done by hand if desired, and reheats very rapidly by reason of the heat stored in the chamber and reel. The chamber is preferably heated by a nichrome heating element, and this heating may be continuous or intermittent. In the latter case the chamber may be more conveniently handled by the operator, because of the absence of the supply wires. The chamber may also be similarly heated continuously or intermittently by other means such as by gas, the invention contemplating broadly the use of a portable heating chamber with a reel therein carrying a flexible heating element or the use of the reel without the chamber, and any and all means for heating the reel or chamber.

Certain embodiments of the invention are illustrated in the accompanying drawings, 50 wherein:

Figure 1 is a vertical section through one form of device; Fig. 2 is a partial side elevation and partial section on the line II—II of Fig. 1; Fig. 3 is a partial face view of the 55 heating element; Figs. 4 and 5 are enlarged views showing portions of the flexible heating members which may be employed; and Fig. 6 is a partial section through a modified form of construction. 60

As shown in Figs. 1 and 2, the casing of the device consists of a pair of sheet metal shells 1 and 2 with an insulating material 3 therebetween, such insulating material being any suitable refractory material which 65 is relatively non-conducting, such as asbestos or kieselguhr. Extending transversely of the casing is a shaft 4 mounted in the bearings 5 and 6 located upon the outside of the casing. The shaft 4 is preferably 70 made hollow so that there will be a less tendency to overheat the bearings and such bearings are preferably of the ball or roller type, which are less affected by heat than solid bearings. The left hand end of the shaft 75 is secured to a clockspring 7 mounted in a casing 8 adapted to bring the reel carried by the shaft back to starting position when the wire which has been withdrawn from the casing is released. 80

The reel itself comprises a solid block of metal 9, upon which the wire or chain 10 is wound, as indicated in Fig. 1. It is desirable that the block 9 should be solid so as to provide a large amount of stored heat 85 for heating the wire or chain after it is withdrawn inside the casing. In case a wire or cable is used it should, of course, be relatively as flexible as possible, and to this end it is preferably of the woven type, as indicated in Fig. 5. A relatively large wire may thus be used which retains a large amount of heat and renders the cracking off relatively easy. Various materials may be used, but the preferred material is nichrome, 90 which does not oxidize and is practically 95

indestructible. In some cases it may be desirable to use a chain instead of the wire or cable, such a chain being illustrated in Fig. 4. This gives a very flexible member, 5 which is desirable, but one which does not hold the heat as long as a wire or cable of the same weight and does not give as good contact against the glass.

The heating element preferably comprises 10 a porcelain ring 12, having a groove 13 on each side (Fig. 1) and a plurality of transverse grooves 14. In these grooves is wound the heating wire 15, also preferably of nichrome, the ends of these wires leading to 15 suitable terminal block 16 on the outside of the casing, to which the cable 17 carrying the leading in wires is attached.

A slot 18 is provided through one side of the casing and the porcelain ring, to permit 20 the withdrawal of the cable or wire, as indicated in Fig. 2. The free end of this wire is provided with a ball 19 or other suitable means which may be readily grasped by the hand of the operator. Another ball 20 is 25 also preferably secured near the end of the wire, which serves as a stop to prevent the wire from being drawn into the casing too far. Enough of the wire is thus left to project from the casing so that the end does not 30 become too warm to handle without inconvenience. Various other means might obviously be provided for securing a cool end upon the wire. In order to conveniently manipulate the casing a handle 21 is secured 35 thereto.

In operating the device current is supplied to the heating element until the wire or chain becomes sufficiently heated, after which the cable is withdrawn from the casing 40 and passed around the article to be severed, such, for instance, as a glass cylinder. The contact of the wire or chain with the glass heats it so that it may be readily capped or cracked off along the 45 line of contact. After the operation is completed the free end of the wire is released and the spring on the casing winds the cable back into the reel, where it becomes reheated for another operation, this 50 reheating operation occurring rapidly because of the heat retained in the casing and in the reel upon which the wire is wound.

Fig. 6 illustrates a modified construction in which the heat is accomplished by means 55 of a gas jet. In this construction the casing 22 and reel 23 are the same as in the other construction, but the electric heating element is omitted and an opening 24 provided in the casing, through which the end 60 25 of a Bunsen burner projects. A number of devices can be employed at the same time so that one of them is always ready for use, and it is not necessary to reheat after each severing operation, as sufficient 65 heat will be retained in the casing and reel

to reheat the wire for a number of operations before it again becomes necessary to place the device over a burner.

In this construction a suitable base 26 is provided for the casing, so that it will rest 70 securely upon the supporting table 27, which carries the burner. This form of construction is more convenient for the operator than one in which gas supply pipes are connected to the casing for giving continuous heat thereto. It also has the same 75 advantage over the type of construction to which the electric leads are continuously connected, although it is possible to heat the device intermittently by electricity and 80 detach the leads during the use of the apparatus, if so desired.

What I claim is:

1. In combination in a glass cracking off device, a heating chamber, a reel in the 85 chamber, a flexible cracking off member wound on the reel and adapted to be withdrawn from the chamber, and means for heating the chamber.

2. In combination in a glass cracking off device, a heating chamber, a reel in the chamber, a flexible cracking off member wound on the reel and adapted to be withdrawn from the chamber, a spring tending 95 to turn the reel and wind the said member upon the reel, and means for heating the chamber.

3. In combination in a glass cracking off device, a heating chamber, a reel in the chamber, a flexible cracking off member 100 wound on the reel and adapted to be withdrawn from the chamber, and an electrical heating element for heating the chamber.

4. In combination in a glass cracking off device, a heating chamber, a reel in the 105 chamber, a flexible cracking off member wound on the reel and adapted to be withdrawn from the chamber, a spring upon the outside of the chamber tending to turn the reel and wind said member upon the reel, 110 and means for heating the chamber.

5. In combination in a glass cracking off device, a heating chamber, a reel in the chamber, a flexible cracking off member wound on the reel and adapted to be withdrawn from the chamber, a spring upon the outside of the chamber tending to turn the reel and wind said member upon the reel, 115 and means for heating the chamber.

6. In combination in a glass cracking off device, a heating chamber, a reel in the chamber, a flexible cracking off member comprising a plurality of strands of fine wire woven together and adapted to be withdrawn from the chamber, and means 120 for heating the chamber.

7. In combination in a glass cracking off device, a reel, a flexible metal cracking off member on the reel, means for applying heat so that the flexible member is heated 125

130

on the reel to a temperature such that it will crack off a glass article when withdrawn from the reel and applied to such article, and means for winding the flexible member back on the reel after the cracking off operation.

8. In combination in a glass cracking off device, a reel, a flexible metal cracking off member on the reel, means for applying heat so that the flexible member is heated

on the reel to a temperature such that it will crack off a glass article when withdrawn from the reel and applied to such article, and a spring for turning the reel to wind the flexible member thereon.

15

In testimony whereof, I have hereunto subscribed my name this 1st day of November, 1919.

HARRY F. HITNER.
